UNITED STATES PATENT OFFICE

2,407,128

MAIL BOX

Eugene J. Axnix, South Bend, Ind., assignor of fifteen per cent to Dan Preger, fifteen per cent to David Preger, and fifteen per cent to Elizabeth Kuzmich, South Bend, Ind.

Application April 26, 1945, Serial No. 590,320

1 Claim. (Cl. 232—17)

1

The present invention relates to new and useful improvements in mail boxes designed primarily for use for the home and rural delivery of mail and the invention has for its primary object to provide an upwardly swinging front cover for the box in order that the contents of the box may be easily and conveniently removed without difficulty.

A further object of the invention is to provide a mail box of this character embodying means for supporting magazines, newspapers and other relatively large articles and also embodying means for supporting mail in a conveniently exposed position for collection by a postman.

A further object of the invention is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a front elevational view.

Figure 2 is a top plan view.

Figure 3 is a vertical sectional view taken substantially on a line 3—3 of Figure 1.

Figure 4 is a transverse sectional view taken substantially on a line 4—4 of Figure 1.

Figure 5 is a fragmentary side elevational view of the lower portion of the main box, and

Figure 6 is a perspective view of the catch.

Referring now to the drawings in detail wherein for the purpose of illustration I have disclosed a preferred embodiment of the invention, the numeral 5 designates an attaching plate adapted for attaching to the side of a house, post or other suitable supporting structure and provided at its lower edge with a forwardly projecting shelf 6.

To the front surface of the attaching plate is secured upper and lower spacing blocks 7 and 8 to the front edge of which is secured the rear wall 9 of a mail box 10, said rear wall of the mail box being attached in any suitable manner and supported at its lower end on the shelf 6.

The mail box 10 includes a top wall 11 and side walls 12 connected to each other in any suitable manner, the top wall 11 having rearwardly projecting tongues 13 positioned outwardly at opposite sides of the back wall 9 and pivoted thereto

2

by means of a pin 14 below the upper edge of said back wall.

The mail box 10 also includes a bottom 15 having a sloping false bottom 15a secured at the lower portions of the side walls 12 and against which is positioned the lower edge of a transparent front wall 16. The front wall 16 is held in position between the side walls 12 by means of vertical retaining strips 17, a lower horizontal retaining strip 18 and lugs 19 projecting inwardly from the side walls 12 behind the front wall 16. The upper edge of the front wall 16 is spaced below the top wall 10 as shown to advantage in Figure 3 of the drawings to provide a mail slot through which mail may be deposited into the box for resting on the sloping false bottom 15a.

In order to remove the mail from the box the lower edge thereof is swung upwardly and forwardly as indicated by the arrow in Figure 3 of the drawings whereby the sloping false bottom 15a will deposit the mail onto the shelf 6 and may then be conveniently removed.

The rear edge of the upper wall 11 is inclined as indicated at 21 to substantially close the space between the top wall 11 and the rear wall 9 when the box is in its closed position and permitting upward swinging movement of the box a distance sufficiently for removing the mail therefrom.

30 The space between the attaching plate 5 and the rear wall 9 of the box forms a chamber 22 therebetween which is open at each side and in which substantially large pieces of mail may be placed.

35 A pair of arms 23 are pivotally attached at one end to the sides of the bottom wall 15 by means of pins 24, the outer ends of the arms being curved upwardly as indicated at 25 and when moved in their outwardly projected positions as shown in Figure 3 of the drawings the arms provide support for newspapers, magazines and the like indicated at 26, such articles being supported in front of the mail box 10.

40 A spring catch 27 projects outwardly from the front edge of the shelf 6 to frictionally engage the lower edge of the box 10 to retain the latter in its closed position.

The upper edge of the rear wall 9 is formed with a slot 28 by means of which letters or the like 29 may be inserted for collection by the postman, said letters constituting outgoing mail.

45 It is believed the details of construction, operation and advantages of the device will be readily understood from the foregoing without further detailed explanation.

In view of the foregoing description taken in conjunction with the accompanying drawings, it is believed that a clear understanding of the construction, operation and advantages of the device will be quite apparent to those skilled in the art.

It is to be understood, however, that even though there is herein shown and described a preferred embodiment of the invention the same is susceptible to certain changes fully comprehended by the spirit of the invention as herein described and the scope of the appended claim.

Having thus described the invention, what is claimed is:

In a device of the class described, a fixed shelf, a box having a deposit opening therein and a back upstanding from said shelf and fixed thereto, said box including a body having a bottom resting on said shelf and a top swingably mounted on said back whereby said body may be swung upwardly and forwardly of said shelf to cause contents of the body to be deposited on the shelf, said body having a false bottom sloping toward said back to facilitate deposit of the contents of the box onto said shelf.

EUGENE J. AXNIX.
